DESIGN FOR A COMBINED WATCH TESTING AND DISPLAY DEVICE OR THE LIKE

Daniel Forbes Ebbert, Wheeling, W. Va.

Application August 2, 1941, Serial No. 102,649

Term of patent 14 years

To all whom it may concern:

Be it known that I, Daniel Forbes Ebbert, a citizen of the United States and a resident of Wheeling, in the county of Ohio and State of West Virginia, have invented a new, original, and ornamental Design for a combined Watch Testing and Display Device or the like, of which the following is a specification, reference being had to the accompanying drawing, forming part thereof, in which:

Fig. 1 is a front elevational view of a combined watch testing and display device or the like, showing my design;

Fig. 2 is a side elevational view thereof; and
Fig. 3 is a top plan view thereof.

I claim:

The ornamental design for a combined watch testing and display device or the like, substantially as shown.

DANIEL FORBES EBBERT.
